FOOT REST FOR SHOE SHINE PARLORS

Original Filed Oct. 24, 1922

FIG. 1.

FIG. 2.

FIG. 3.

INVENTOR
FIG. 4. ALLAN R. P. JOHNSON
BY

Atticus Langille
ATTYS.

UNITED STATES PATENT OFFICE.

ALLAN ROLAND PYE JOHNSON, OF TORONTO, ONTARIO, CANADA, ASSIGNOR OF ONE-HALF TO CHARLES TILLEY AND HERBERT VICTOR TILLEY, BOTH OF TORONTO, ONTARIO, CANADA.

FOOT REST FOR SHOE-SHINE PARLORS.

Application filed October 24, 1922, Serial No. 596,618. Renewed May 2, 1925.

To all whom it may concern:

Be it known that I, ALLAN ROLAND PYE JOHNSON, a subject of the King of Great Britain, and a resident of the city of Toronto, in the county of York, in the Province of Ontario, Canada, have invented certain new and useful Improvements in Foot Rests for Shoe-Shine Parlors, of which the following is the specification.

16 My invention relates to improvements in foot rests for shoe shine parlors and the object of the invention is to devise a foot rest which may be utilized as a step by which the customer may mount upon the 15 high seat of the shoe shine chair with a minimum amount of effort and it consists essentially of the following arrangement and construction of parts as hereinafter more particularly explained.

20 Fig. 1 is a side elevation of my device applied to a shoe shine chair.

Fig. 2 is a front elevation.

Fig. 3 is an enlarged detail, shown mostly in elevation, of my foot rest showing it 25 utilized as a step in the full lines and in a foot rest position by dotted lines.

Fig. 4 is a front elevation of the parts as illustrated in Fig. 3 showing the upper portion of one of the standards in section.

30 Fig. 5 is a plan view of the parts shown in Figs. 3 and 4.

In the drawings like characters of reference indicate corresponding parts in each figure.

35 1 indicates a shoe shine chair of ordinary construction which is mounted upon a raised platform 2, which platform is provided with a stepped-up portion 3 located beneath the chair. 4 and 5 are standards secured to 40 the platform 2 in front of the chair 1. The standards 4 and 5 are provided with jawed upper ends 6 through each of which extends a cross pin 7. 8 is my combined step and foot rest member provided with side arms

45 9 and 10 having segmental circular inner ends 11 provided with centre orifices 12 and enlargements 13 and 14 forming stop projections for a purpose which will hereinafter appear.

The arms 9 and 10 extend horizontally and 50 at their free ends curve into a vertical direction to carry the foot rest portions 15 and 16. 17 is a step plate extending between the arms 9 and 10 and mounted upon that side of the arms opposite to the vertically extending portions of such arms to 55 bridge the space therebetween.

18 is a handle by which the device may be operated.

When the device is not in use the arms 60 9 and 10 are swung into the full position shown in Figure 3 so that the foot rest portions are supported upon the stepped-up portion 3. The customer then may step upon the platform 2 then onto the step 17 65 which is located in such a position as to enable him to easily seat himself upon the shoe shine chair 1. The arms 9 and 10 are further supported in this position by the enlargements 14 bearing against the stands 70 4 and 5.

When the customer is seated in position the operator grasps the handle 19 and swings the foot rest to the dotted position shown in Fig. 3. The customer may then place 75 his feet upon the foot rests 15 and 16 and when his shoes have been shined the foot rest is returned to its original position to enable the customer to easily descend.

What I claim as my invention is:

1. A foot rest for shoe shine parlors comprising a platform provided with an up-standing ledge, a standard support located in front of the ledge, a member swung upon the upper end of the standard support 85 and having its end curved into a vertical direction, a foot rest carried upon the vertically extending portion adapted to rest upon the platform ledge, and a step member carried upon the opposite side of the 90 swung member to the vertically extending portion.

2. A foot rest for shoe shine parlors comprising a platform provided with an up-standing ledge, a standard support located 95 in front of the ledge, a member swung upon the upper end of the standard support and having its end curved into a vertical direc-

tion, a foot rest carried upon the vertically extending portion adapted to rest upon the platform ledge, a step member carried upon the opposite side of the swung member to the vertically extending portion, and stop enlargements carried by the swung member and adapted to bear against one side of

the standard when the swung member is swung in one direction and against the opposite side of the standard when the swung member is swung to the opposite side of the standard. ¹⁰

ALLAN ROLAND PYE JOHNSON.
